LOADING APPARATUS

Harry Wadsworth Morgan, Wilmington, Del., assignor to Triumph Explosives, Inc., Elkton, Md., a corporation of Maryland

Application March 30, 1942, Serial No. 436,867

3 Claims. (Cl. 86—31)

This invention relates to ammunition loading apparatus and more particularly to apparatus for receiving projectiles or shells while they are being filled with molten explosive material.

It is a general object of the present invention to provide novel and improved apparatus for use while loading shells with molten explosive material.

More particularly it is an object of the invention to provide means for sealing the fuse opening of a hollow projectile while molten explosive is being poured into the opposite end of the same.

It is a further object of the invention to provide apparatus for sealing the lower opening of and supporting a hollow projectile while the same is being charged with a molten explosive.

As an important feature of the invention may be mentioned the provision of an extension on the fuse opening plug of a core or former member adapted to provide a recess in the explosive material, after the same has hardened, of an appropriate size to accommodate portions of the fuse and the booster associated therewith.

Another important feature of the invention comprises the arrangement of a plurality of combined plugs and formers on a suitable mounting base together with mechanism for simultaneously actuating the plug expanding means which serve to seal the threads of the fuse opening against the entrance of the molten explosive material.

Other and further objects and features of the invention will be more apparent to those skilled in the art upon a consideration of the accompanying drawings and following specification wherein is disclosed a single exemplary embodiment of the invention with the understanding that such modifications may be made therein as fall within the scope of the appended claims without departing from the spirit thereof.

In said drawings:

Figure 1 is a plan view of apparatus constructed in accordance with the present invention and having the central portion in horizontal section just below the level of the cover plate to illustrate mechanism beneath the same;

Figure 2 is a vertical section in the plane of line 2—2 of Figure 1;

Figure 3 is an enlarged vertical section through one of the combined plug mould devices and its associated base mechanism with the projectile shown thereon as initially positioned; and

Figure 4 is a view similar to Figure 3 showing the plug mechanism expanded to seal the threads of the fuse opening in the projectile.

Numerous methods have been suggested and

actually used for charging high explosive material into projectiles such as artillery shells, aeroplane bombs, grenades, mines, and the like, but most of these have not been wholly satisfactory because of difficulties or dangers encountered in their use or because of the relatively slow operations necessary in carrying out the same.

In accordance with the present invention an improved method and apparatus for carrying out the same is provided whereby the shells may be loaded without the difficulties and dangers encountered in previous methods and with greater rapidity, accuracy and ease.

The method of the present invention and the apparatus for use therewith is applicable only to shells or projectiles adapted to be charged with an explosive material in the molten form and in which openings are provided at both ends. Where such shells have been loaded heretofore it has been necessary to plug one opening thereof and to pour the explosive in the opposite opening, but the means for closing the lower opening were engageable with the threads thereof by a slow threading operation in order to fill the threads and prevent the entrance of the explosive material into the same. These threads which normally accommodate the fuse are quite lengthy to provide suitable strength for retaining the fuse at the instant of explosion and hence necessitated a number of turns of the plug for seating therein. The individual plugs did not provide for supporting the shells nor did they always ensure a suitable aperture or recess in the explosive material to receive the booster associated with the fuse. It is highly important that this recess be provided during the pouring and that it be accurately centered and sized to just receive the booster and yet eliminate the possibility of frictional contact therewith during the operation of screwing the fuse in position. If the cavity for the booster is not provided during the moulding, a slow and highly dangerous drilling operation to provide it has been followed.

In accordance with the present invention a mechanism is provided for supporting and plugging and forming the booster cavity in a plurality of projectiles simultaneously. For a better understanding of the same, reference should be had to the accompanying drawings.

First considering Figures 3 and 4. Here the portion of the projectile which cooperates with the apparatus of the present invention is illustrated. The shell proper shown at 10 is provided with an enlarged central chamber 11 into which it is desired to fill the molten explosive material.

The nose 12 of the shell is axially bored at 14 and threaded as at 15 to receive the shank of a suitable fuse (not shown). The fuse cooperates with a booster which extends into the cavity 11 for a substantial distance and provision must be made in the hardened explosive material to closely receive this booster. In order to provide the necessary booster cavity, to shut off the threads 15 against the influx of the molten explosive, and to support and position the projectile during the filling operation, a plurality of the devices shown in Figures 3 and 4 are assembled into a mechanism best illustrated in Figures 1 and 2. The individual devices will be first described and then the assembly of the same detailed.

The base plate 16 of the apparatus is provided with a circular aperture 17 for each of the projectile supporting devices and into this aperture fits the lower enlarged end 18 of a cylindrical stud 19 equipped with the wide radial flange 20 adapted to rest on the surface of the base plate and be secured thereto by fastening elements 22. The stud 19 is of such a diameter as to have a free fit into the threads 15 of the fuse opening in the lower end of the projectile. It is centrally drilled as at 23 to accommodate with a sliding fit, the stem 24 having attached at its upper end the head or mould 25 of exactly the shape and size desired for the booster recess in the explosive. The top end 26 of the stud and the lower end 27 of the head have flat faces confronting each other and resting on opposite surfaces of an interposed resilient gasket or washer 30 perforated to fit over the stem 24 as clearly shown. In its relaxed form this washer also loosely fits the threaded bore and is so positioned longitudinally that its upper surface is slightly above the ends of the threads 15, as a result of the nose end 31 of the projectile resting on the upper surface of the flange 20 as an entrance limiting means.

If after setting a projectile over the stud a downward tension be applied to the stem 24 the head 25 will be drawn toward the upper end of the stud compressing the washer longitudinally and expanding the same laterally to closely engage into the threads 15 as shown at 33 effecting, at their exact upper end, a close seal impervious to the viscous molten explosive which may be TNT or some material of a like nature. The outside configuration of the head or former 25 is such as to determine the proper size of recess for the booster, but its lower end is enlarged as at 34 to the same diameter as the stud whereby better compression of the gasket is had. It will be noticed that during the tensioning operation of the stem that the gasket is enlarged and at the same time reduced in thickness. With the drawing-down of the head 25 the gasket engages the threads and tends to hold the projectile down with its nose tightly against the flange 20 so that it is rigidly supported against any displacement during the pouring operation.

As simple means for providing the relative movement between the head and the stud necessary to compress the gasket, the stem 24 is shown as flattened to be received in a kerf 36 of a cam element 37 pivoted at 38 to the lower end of the stem and having the eccentric arcuate surface 39 engaging against the portion 18 of the stud. In the relaxed condition of the gasket the cam assumes the position shown in Figure 3, while when the same is rotated through an angle of approximately 30° to the position shown in Figure 4, it provides the necessary amount of stem

movement to expand the gasket the desired amount. The solid lower end of the cam is drilled as at 40 to accommodate an actuating rod 41 which will be described in connection with the assembled form of the device.

Referring now to Figures 1 and 2, it will be seen that the base plate 16 may be made of any desired size to accommodate a plurality of the plug members preferably in a series of parallel rows with the members in adjacent rows next to each other for convenience in the multiple operation of the cams.

The base plate is supported by peripheral angle bars 43 and 44 suitably secured thereto as by welding or otherwise to form in effect a hollow inverted pan. The lower flanges of the angles may be drilled to accommodate fastening devices if necessary.

Four rows of six studs each are illustrated in Figure 1. Here it will be noted that the actuating rods 41 which pass through the cams 37 connect these cams in pairs, one in each adjacent row. Each rod 41 passes loosely through an opening in a longitudinal bar member 46 as shown. One of these bars runs between each pair of stud rows whereby longitudinal movement of the same will actuate the several cams to either tensioned or released position.

The two bars 46 shown in Figure 1 are connected together by a transverse member 47 as clearly seen in Figures 1 and 2 and provision is made to move this rod member laterally by the action of a pivoted lever 48 mounted near the center of the plate. The lower end of the lever is equipped with an enlarged head 49 which is bifurcated, providing the two spaced arms 50 and 50'. A casting 53 is secured to the base plate 16 by fastening elements 54 passing through flanges 55 thereon. The base plate is provided with an appropriate opening 60 to accommodate the depending wings of the flanges 55 which receive the pivot pins 51 cooperating with arms 50 and 50' well below the surface of the base plate. The forked member 49 fits in the opening 52 in casting 53 and there carries a movable pivot pin 61 which engages one end of a link 62 which passes through the slot between the arms 50 and 50' and whose other end is journaled on the member 47.

An inspection of Figure 2 will show that when the lever is in the position illustrated in solid lines the rigid link 62 has moved the cross member 47 to its maximum left-hand position setting all the cams at their released position. When the lever is pulled to the right to the dotted line position illustrated in Figure 2, the link 62 is placed under tension, moves the member 47 to the right and places all of the cams in their gasket expanding position. The lever 48 in reaching the dotted line position, where it is stopped against a portion of the casting 53, carries the pivot pin 61 for the right hand end of the link from one side of the pivot pins 51 to the opposite thereby causing the link to pass over dead center and lock the lever in the right-hand position so that it can be released by the operator and still retain the gaskets all compressed to secure a plurality of shells in position for loading.

The molten material is now poured into each of the shells by appropriate apparatus and the whole mechanism just described is set aside until the material has cooled and hardened when a releasing of the lever allows the gaskets to return to their relaxed condition so that the shells are

free to be removed in their finished form with the proper shaped recesses in the now hardened explosive material of just the proper size, shape and central location to closely receive the boosters associated with the fuses. The threads of the fuse openings are entirely clean because the explosive material has been carefully excluded from them during the pouring.

The whole apparatus is simple, cheap and effective and can be used by unskilled labor with no chance of making a mistake in operation.

Having thus described the invention, what is claimed as new and desired to be secured by Letters Patent is:

1. Shell loading apparatus comprising, in combination, a hollow base including a flat top plate having a plurality of holes arranged in parallel rows, a plug and mould for the fuse opening of a hollow projectile while filling the same with a molten explosive being provided for each hole; said plugs and moulds each including a hollow stud adapted to freely enter said opening, a mounting flange on said stud secured to the plate, covering one of the holes and positioned to limit the stud entrance into the shell opening, a stem 10 slidable through said stud and having a head extending beyond the outer end of the stud, a resilient washer on said stem between the head and stud, means to tension the stem to compress the washer longitudinally and expand the same laterally to engage the walls of the opening; an operating lever pivotally mounted on said plate, and linkage associating each of said means with said lever for simultaneous expansion of said washers.

2. Shell loading apparatus comprising, in combination, a hollow base including a flat top plate having a plurality of holes arranged in parallel rows, a plug and mould for the fuse opening of a hollow projectile while filling the same with a molten explosive being provided for each hole; said plugs and moulds each including a hollow stud adapted to freely enter said opening, a

mounting flange on said stud secured to the plate, covering one of the holes and positioned to limit the stud entrance into the shell opening, a stem slidable through said stud and having a head extending beyond the outer end of the stud, a resilient washer on said stem between the head and stud, means to tension the stem to compress the washer longitudinally and expand the same laterally to engage the walls of the opening; an operating lever pivotally mounted on said plate, cross rods connecting said means in pairs, longitudinal members connecting the rods, an operating lever, and link means associating said members and lever whereby all washers are compressed simultaneously by movement of the lever.

3. Shell loading apparatus comprising, in combination, a hollow base including a flat top plate having a plurality of holes arranged in parallel rows, a plug and mould for the fuse opening of a hollow projectile while filling the same with a molten explosive being provided for each hole; said plugs and moulds each including a hollow stud adapted to freely enter said opening, a mounting flange on said stud secured to the plate, covering one of the holes and positioned to limit the stud entrance into the shell opening, a stem slidable through said stud and having a head extending beyond the outer end of the stud, a resilient washer on said stem between the head and stud, means to tension the stem to compress the washer longitudinally and expand the same laterally to engage the walls of the opening; an operating lever pivotally mounted on said plate, cross rods connecting said means in pairs, longitudinal members connecting the rods, an operating lever, and link means associating said members and lever whereby all washers are compressed simultaneously by movement of the lever, said lever and link having pivots arranged to move over center to lock the lever in "compression" position.

HARRY WADSWORTH MORGAN.
